RAZOR BLADE SHARPENER

Andrew F. Bell, Troy, N. Y., assignor to Behr-Manning Corporation, Troy, N. Y., a corporation of Massachusetts

Application February 24, 1937, Serial No. 127,477

7 Claims. (Cl. 51—122)

The invention relates to sharpeners for razor blades and similar articles.

One object of the invention is to provide a razor blade sharpener whereby used razor blades, particularly of the double edged wafer type, may be resharpened. The double edged wafer blades referred to are those well known to the public as blades manufactured by The Gillette Safety Razor Company and other blades of similar characteristics. Another object of the invention is to provide a razor sharpener which may be used to resharpen single edged flat safety razor blades. Another object of the invention is to provide a blade sharpener of universal characteristics whereby many different types of blades may be sharpened.

Another object of the invention is to provide a razor blade sharpener including a honing wheel. Another object of the invention is to synchronize the rotation of a honing or abrasive wheel with rectilinear movement of a blade across it in order to duplicate results in the sharpening of blades irrespective of variations in the actuation of the device by the user. Another object of the invention is to provide a device of the character specified such that manual operation will result in a grinding or honing speed of the wheel of fairly constant amount in the hands of different users. Another object of the invention is to provide a device of the character specified with two honing wheels and means for placing either one of the honing wheels in operative position by relatively simple adjustment or change of parts. Another object of the invention is to provide a razor blade sharpener with both a honing and a stropping wheel, both interchangeably available.

Another object of the invention is to provide a device of the character indicated with adequate safeguards to prevent injury to the user. Another object of the invention is to provide a device of the character indicated of great efficiency in practical operation and capable of producing a very sharp and highly effective cutting edge for razor blades and the like. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which are shown several of the many possible embodiments of the mechanical features of this invention,

55 Figure 1 is a vertical longitudinal sectional

view, on an enlarged scale, of a blade sharpener constructed in accordance with the invention;

Figure 2 is a sectional view taken on the line 2—2 of Figure 1;

Figure 3 is a fragmentary plan view of the 5 driving gearing for the wheels;

Figure 4 is a plan view of the device with the cover of the box removed;

Figure 5 is a fragmentary plan view of the 10 inner wheel and control therefor;

Figure 6 is a fragmentary side elevation of the 15 control knob for the inner wheel;

Figure 7 is a view similar to Figure 6, showing the parts in that position in which the central wheel is depressed;

Figure 8 is a vertical axial sectional view of the 20 wheels and their mounting such as is shown in Figure 1 but showing the parts in that position in which the central wheel is depressed;

Figure 9 is a fragmentary longitudinal vertical 25 sectional view taken on the line 9—9 of Figure 2;

Figure 10 is a cross sectional view taken on the line 10—10 of Figure 1;

Figure 11 is a fragmentary plan view of the 30 blade holder;

Figures 12 and 13 are fragmentary sectional 35 views taken on the lines 12—12 and 13—13, respectively, of Figure 11;

Figure 14 is a fragmentary plan view of a modification of the invention in which a single annulus device comprising two wheels of the same diameter are employed, the change from one to the other being made by picking off the wheels and turning them over;

Figure 15 is an axial sectional view of the modification of Figure 14, taken on the line 15—15 of Figure 14;

Figure 16 is a plan view of a blade holder for a "Gem" type of razor blade;

Figure 17 is a longitudinal sectional view 40 through the holder of Figure 16;

Figures 18 and 19 are transverse sectional views taken along the lines 18—18 and 19—19, respectively, of Figure 16;

Figures 20, 21 and 22 are fragmentary vertical 45 sectional views in three different planes of the escapement pawls for the blade holder, taken respectively on the sections 20—20, 21—21 and 22—22 of Figure 4;

Figure 23 is a fragmentary plan view of one 50 end of the box, with the cover of the box and the cover guard removed, illustrating a modified form of escapement pawls and actuating device for the blade holder;

Figure 24 is a fragmentary sectional view, taken 55

on line 24—24 of Figure 23, showing the parts on an enlarged scale;

Figure 25 is a fragmentary sectional view on the same scale as Figure 24, the section being taken on the line 25—25 of Figure 23;

Figure 26 is an end elevation of the modified form of escapement pawls and associated actuating mechanism, the view being taken from the line 26—26 and looking in the direction of the arrows thereon in Figure 24;

Figure 27 is a sectional view on a further enlarged scale, the section being taken along the line 27—27 of Figure 23;

Figure 28 is a view similar to Figure 23, showing the further modification of the escapement pawls and actuating mechanism;

Figure 29 is a sectional view, taken along the line 29—29 of Figure 28;

Figure 30 is a sectional view, taken along the line 30—30 of Figure 28; and

Figure 31 is an end elevation of one of the escapement pawls and actuating mechanism of Figure 28.

Referring first to Figures 1, 2 and 4, I provide a box 30 of parallelopipedal shape, for example of integral structure made by die casting suitable metal or of molded resinoid. Referring now to Figure 1, a rivet 31 is located near but not exactly in the center of the box, which rivet pivotally mounts a pair of gears 32 and 33 that are fastened to each other. Referring now to Figure 3 in connection with Figure 1, the small gear 33 is actuated by a rack 34 while the large gear 32 meshes with a small gear 35 which is mounted on a stud 36 extending upwardly from the bottom of the box and fastened thereto by means of a nut 37.

Referring now to Figure 2, the box 30 has a pair of benches 40, one along each long side thereof. A sheet metal false bottom 41 is fastened to the bottom of the benches 40 by means of four screws 42, the heads of which fit in recesses 43. The false bottom 41 has an integral portion 45 extending vertically upward and in a plane perpendicular to the plane of the false bottom 41.

Referring now to the right-hand side of Figure 1, I provide a carriage 46 made of sheet metal. This carriage, as shown in Figures 1 and 2, is U shaped in cross section, comprising a bottom portion 47 which is under the false bottom 41 and two side portions 48 located alongside the sides of the box 30. The false bottom 41 does not extend, along its entire length, to the sides of the box 30 but rather terminates short thereof, leaving just enough room for the upwardly extending sides 48 of the carriage 46. The rack 34 is integrally attached as by pins 49, Fig. 2, to the bottom 47 of the carriage 46 so that it is moved longitudinally of the box whenever the carriage is moved.

Comparing Figure 1 with Figure 4, it will be seen that there is a cut-out 50 in the bottom 47 of the carriage 46 so that the carriage may be moved substantially the entire length of the box in spite of the upwardly extending stud 36.

Referring to Figure 4, connecting the upwardly extending portions 48 of the carriage 46 is an inverted channel member 51 which, as better shown in Figure 1, supports the front end of a blade holder 52. The blade holder 52 is a flat piece of sheet metal having a portion 53 extending into the channel 51 located between two flat springs 54 which are mounted in the channel 51 having portions 55 which extend into slots in the sides of the channel 51. Thus the blade holder 52 is pivotally mounted and is resiliently held in a

horizontal position but can be readily turned over. The other end 56 of the blade holder 52 is pivotally mounted in an L shaped cross piece 57 extending between the sides 48 of the carriage 46.

I provide a slidable cover guard and actuator 60 which may be shaped as shown in the several views. This may be made of molded resinoid or it may be made of sheet metal or of any other substance, as desired. It has trunnions 61 extending into slots 62 formed on upward extensions 63 of the sides 48. Thereby, when the cover 65 of the box is removed, the slidable cover guard and actuator 60 may be swung upwardly. At that time a blade may be put in position on the blade holder 52.

Referring now to Figures 1 and 11, a hook 67 is articulated to the blade holder 52 by rivet 67 and by means of this hook a clamping member 68 is pivotally connected to the blade holder to allow of vertical as well as lateral motion. Referring to Figure 11, the holder 52 has a turned-over tab 70 and the clamping member has a tab 71 whereby the holder 52 and clamping member 68 may be interlocked together by relative lateral movement. Still referring to Figure 11, four tabs 72 extend from the blade holder 52 in such positions as to hold the re-entrant angle shoulders of a Gillette type of razor blade 75. Thus the clamping member 68 may be swung sidewise and then upwardly to allow a blade 75 to be placed in position, as shown in Figure 11, and then it may be laterally moved into locking position so that the blade is held from movement upwardly by the clamping member 68 and the blade is held from movement in the plane thereof by the tabs 72. At the same time the blade holder including the holder 52 and the clamping member 68, while resiliently held by the springs 54 in the horizontal position shown in the drawings, may be turned over and, furthermore, may be tilted. Compare Figures 10 and 11.

It has been noted that the cover guard 60 is connected to the carriage 46 by a trunnion and slot connection. This permits not only angular movement of the cover guard 60 but also relative rectilinear movement between it and the carriage 46.

In the actuation of the razor sharpener, the user holds the entire box 30 in one hand and, having removed the cover 65, holds the cover guard and actuator 60 with the fingers of the other hand. The user then pushes the cover guard actuator 60 back and forth. The first result of this action is to move the cover guard 60 relative to the carriage 46. This is relied on, as will hereinafter be explained, to incline the blade holder 52 to the horizontal in order to present the blade 75 against the honing wheel. As the parts are moved in one direction, the blade holder 52 is inclined in a given direction, and upon reversal the blade holder is inclined in the opposite direction. For the relative rectilinear motion between the cover guard 60 and carriage 46, I provide ways for the cover guard comprising, as best shown in Figures 1 and 2, sheet metal members 76 riveted by rivets 77 to the sides 48 and having, as best shown in Figure 2, inward extensions 79 forming a horizontal support for the cover guard 60 and upwardly extending, slightly off-set portions 80 forming the vertical surfaces between which the cover guard 60 may slide. See also Figures 4, 9 and 17.

Referring now to Figures 20, 21 and 22, in one corner of the cover guard 60 I mount a vertically extending rotatable knob 81. This knob 81 has eccentric portion 82 on the bottom thereof. The

eccentric portion 82 fits in a slot in a slide 83. To the bottom and top respectively of the slide 83 are fastened escapement pawls 84 and 85 shaped as shown in these views and also as shown in Figure 2. Referring to Figure 11, extending laterally from the blade holder 52 are arms 86. Referring now to Figure 9, the shape of the escapement pawls 84 and 85, as viewed from the side of the apparatus, is clearly disclosed. Between them is one of the arms 86. The cover guard 60 is shown in its central position of non-actuation. If it is moved forwardly relative to the carriage 46, it will depress the arm 86. This will cause the blade 75 to be tipped so that its left-hand edge, as the apparatus is viewed in Figure 2, will be depressed. Conversely, relative movement of the cover guard 60 in the opposite direction will depress the right-hand side of the blade 75, viewing the parts as in Figure 2. This pressure is a resilient pressure owing to the spring character of the escapement pawls 84 and 85. Referring again to Figures 20, 21 and 22, the slide 83 is supported by a bottom plate 87, and the slide 83 can be adjusted by turning the knob 25 81 to place the escapement pawls 84 and 85 nearer to or farther away from the axis of the blade holder 52, as desired. Thus the pressure on the blade may be adjusted.

The device also includes apparatus to revolve the blade once for each complete reciprocation of the carriage 46 and cover guard 60. Considering now Figures 1 and 2, extending inwardly from the vertical sheet metal portion 45 and rigidly attached thereto is a cam actuator 90. This cam actuator 90 is arcuate in shape in end view, being part of a hollow cylinder, and its front actuating edge is a helix. The actuating cam 90 extends through the L shaped cross piece 57 through an arcuate slot 91 therein when the carriage 46 is in the position shown in the drawings. It will be remembered that when the cover guard 60 is urged to the right in Figure 1, the right-hand side (Figure 2) of the razor blade is depressed. The top portion of the cam 90, therefore, catches the right-hand arm 86. At the same time it should be noted that there is nothing to prevent upward movement of the left-hand arm 86 since the lower escapement pawl 84 is urging it upwardly and there is a gap between the escapement pawls. While the blade was in contact with the rotating honing wheel, the wheel prevented further rotation of the blade holder, but the blade has already left the honing wheel when the cam 90 engages one of the arms 86. Owing to the shape of the actuating cam 90, the entire holder 52 and associated parts is given nearly one-half a revolution, and the movement is completed by the springs 54 which tend to hold the blade holder 52 in flat position. The shape of the escapement pawls 84 and 85 is such that an arm 86 can enter between them from the bottom. Therefore, considering Figure 2, the left-hand side of the razor blade is depressed during forward movement of the cover guard 60 and carriage 46, that is to the left in Figure 1, but resiliently depressed, then the right-hand side of the razor blade 75 is depressed during retrograde movement of cover guard 60 and carriage 46, that is to the right in Figure 1, and as the parts reach the end of this stroke the holder 52 is given a one-half revolution. In this manner all four edges of a double edged razor blade are honed by the rotating wheel to be described and by the rectilinear motion described are traversed over the wheel. Although, as stated,

the upwardly moving arm 86 may enter between the escapement pawls 84 and 85, nevertheless at the end of the turning-over movement of the blade holder 52, the arm 86 that is on the left-hand side as viewed in Figure 2 strikes the bottom of the escapement pawl 84 and only enters between the escapement pawls on the next forward movement of the cover guard 60, which movement moves both pawls 84, 85 forwardly with respect to the arm 86, immediately holding this same arm downwardly during the next forward stroke. Therefore, it will be seen that the escapement pawl 84 acts to prevent continuous rotary movement of the blade holder 52 even if the springs 54 are weak, or if the user actuates the device so violently as to tend to cause the razor holder to whirl.

The razor blade being sharpened is thus reciprocated back and forth in the box 30 whenever the user grasping the cover guard 60 reciprocates it. It is intended that the user shall push the cover guard back and forth, each stroke stopping with the impact of the carriage 46 against raised portions of the benches 40 at each end of the box 30. During what I have termed forward motion, which is from left to right in Figure 1, the left-hand side as viewed in Figure 2 of the blade is urged downwardly. During retrograde motion the right-hand side of the razor blade 75 is urged downwardly. At the end of the retrograde motion and when the razor blade is out of contact with the honing wheel, the blade is flopped over so that in the succeeding reciprocation the other side of the blade is honed. This action continues indefinitely as long as the user cares to reciprocate the parts. I will now describe the actuation and mounting of the honing wheels.

Referring first to the left-hand side of Figure 1, and also to Figure 8, the small gear 35 has a vertical bore so that it may be pivotally mounted on the stud 36. Referring now also to Figure 4, I provide a wheel 100 with a plurality of integral spokes 101, for example three in number. The wheel 100 with its spokes 101 may be a steel stamping; as shown, it is cut in the center portion complementary to the gear 35 and interlocks with it. Fastened to the wheel 100 as by means of pins 102 is a fiber wheel 103, being Z shaped in cross section as clearly shown and being in this illustrative embodiment of the invention of uniform cross section through its entire 360° of arc. So far as certain features of the invention are concerned, I provide a honing wheel 104 and a stropping wheel 103. The distinction is this: The honing wheel 104 is an abrasive wheel which may consist of granular abrasive material bonded with a suitable bond. For example, I prefer to make the honing wheel of finely divided aluminum oxide abrasive grain, that is to say of the order of 400 grit size or finer, bonded together with a shellac bond into a dense and relatively non-porous structure. This, as compared with most grinding wheels, is a very soft wheel including fine grit abrasive and may be properly classed as a honing wheel. On the other hand, the wheel 103 may consist of ordinary so-called hard fiber, or I may use a wheel with a leather surface or the like and it is properly classed as a stropping wheel. A honing wheel actually cuts or abrades although its action is finer and more delicate than a grinding wheel. Nevertheless, the difference may be said to be largely one of degree. On the other hand, a strop acts to align the frayed cutting 75

edge of the razor without removing any metal, and also smoothes, polishes and conditions the cutting edge of the razor for shaving. These distinctions are known in the razor sharpening art and so far as the mechanical features of the invention are concerned, I may use any two wheels desired, for example I might have two honing wheels or a grinding wheel and a honing wheel. In actual practice, however, excellent results are achieved using a honing wheel and a stropping wheel. Sometimes a blade is best sharpened merely with the stropping wheel, sometimes merely with the honing wheel, and sometimes best results will be achieved by using the wheels successively, generally using the honing wheel first.

The wheel 104 is mounted concentric with the wheel 103 and, as shown in Figures 1, 4 and 8, it comprises the wheel itself 104 which is an annulus of abrasive material of cross sectional form as shown, secured to a wheel 105 by any suitable cement or in any other suitable manner. The annular portion of the wheel 105 is L shaped in cross section, as shown, to provide a good support for the wheel 104, and the wheel 105 includes three integral spokes 106 and a central ring or hub 107. This wheel 105 with spokes 106 and center 107 is desirably a sheet metal part, being all in a single plane, excepting for the upturned flanged portion 108 of the rim.

Still referring to Figures 1, 4 and 8, the gear 35 is integrally formed with a sleeve 110. For the interlocking of the gear 35 and sleeve 110 to the hub of the spokes 101, I swage over, as at 111, a portion of the gear teeth of the gear 35. The sleeve 110 mounts the hub 107 of the wheel 105. By upsetting operations I force upwardly three portions 115 of the spokes 101 of the wheel 100. These portions 115 stand perpendicular to the plane of the wheel 100. Extending across the slots 116 left by forcing upwardly the portions 115 are washers 117. On top of the washers 117 are springs 118. In the spokes 106 of the wheel 105 are holes 120 receiving the portions 115. Thus the wheel 105 is locked angularly to the wheel 100 but relative axial movement is nevertheless possible although the springs 118 urge the wheels 100 and 105 apart. I provide a locking adjustment device to position the internal honing wheel at a level just above the level of the stropping wheel 103, as shown in Figure 1, or to position the honing wheel 104 just below the level of the stropping wheel 103, as shown in Figure 8. This device includes an adjustment cam knob 121 which is shown in Figures 1, 4 and 8. The adjustment cam knob 121 consists of a cup-shaped annulus with a knurled outer periphery just fitting over and rotatably mounted upon the outside of the sleeve 110 and having three depending cams 122. Referring now to Figures 4, 5, 6 and 7, the depending cams 122 rest against the hub 107 of the upper wheel 105 and fit in three wide slots 124 or three narrow slots 125. The three slots 124 are located 120° apart and so also are the slots 125. Adjacent slots 124 and 125 are located 60° from each other. The cams 122 are located 120° apart. Consequently rotation of the knob 121 will place all of the cams 122 in the several slots 124 and then all of these cams in all of the slots 125. A sixty degree turning of the knob 121 will change the cams from all of the wide slots 124 to all of the narrow slots 125 and any further sixty degree angular movement will change the cams to all of the wide slots 124. In this particular embodiment of the invention, it is

immaterial which particular cam 122 is in which particular wide slot or narrow slot, respectively. Whenever the cams are in the wide slots 124, the springs 118 force the upper wheel 105 upwardly to the position shown in Figure 1 and whenever the cams 122 are in the narrow slots 125, the wheel 105 is held in a more depressed condition, as shown in Figure 8. Consequently, by means of the control knob 121, the honing wheel 104 may be held just below the level of the top of the stropping wheel 103 or it may be allowed to project just above it. By this simple control, the device can be rapidly shifted from a stropping to a honing device or vice versa.

Still referring to Figures 1 and 8, the control knob 121 is held upon the sleeve 110 by means of a nut 127 which fits on the threaded part of the sleeve 110, as shown, and may be tightened against a shoulder 128. By removing this nut 127, the wheels and associated parts can be quickly disassembled.

The operation of the device has been largely described in connection with the description of the several parts and mechanisms. However, it is noted that the slidable cover guard and actuator 60 is somewhat dome shaped so as to provide room for turning of the razor blade 75 inside of it and it has a couple of inclined sides 130 to the dome portion 131 which may be ribbed, if desired, to provide a firm grip for the fingers. The cover guard and actuator 60 is also a safety device as, when it is in a closed or down position, as shown in all the drawings, the user cannot accidentally touch the razor blade. As a further safety precaution, the cover guard 60 has an arcuate portion 132 which, when the cover guard is raised, locks the blade holder against rotary movement.

In using the device, the user first removes the cover 65 which is provided to keep dirt out of the parts when not in use and to protect them generally. He then slides the clamping member 68 on the rivet 67 away from the blade holder 52 to the dotted line position shown in Figure 11. It may be necessary to reciprocate the carriage 46 once in order to place the clamping member 68 on top, which action will be effected by the cam 90. For the convenience of the user, the clamping member 68 may have the word "Top" stamped thereon or any other convenient designation. A Gillette type of razor blade is then placed between the lugs 72 and the clamping member 68 is swung back into position, sliding the tabs 70 and 71 into frictional engagement with the parts 52 and 68. This placing of a razor blade on the holder 52 under the clamping member 68 may be done in any position of the carriage 46, and the cover guard 60 may be lifted in any position of the carriage 46 to provide access to the holder and clamping member. The cover guard 60 is now swung downwardly and it is reciprocated. The rack 34 which is attached to the carriage 46 rotates the gear 33 which is connected to the gear 32, and the gear 32 rotates the gear 35. Thus the wheels 103 and 104 are rotated whenever the carriage 46 is moved and at a relatively high speed by reason of the fact that the drive is a geared up drive. Furthermore, as the rack 34 is always in engagement with the small gear 33, and the other gears are always in engagement, the ratio of reciprocating motion to angular motion is constant. The wheels 103 and 104 act as fly wheels but, when the carriage 46 strikes the benches, the entire momentum is killed and there is a slight rebound due to the resiliency of the gearing and 75

connections. Owing to the inertia of the wheels and the geared up connection, it is difficult to achieve very high angular velocity of the wheels, and nevertheless it is fairly easy to move them. 5 As the result of these considerations, different users will rotate the wheels at no greatly varying velocities, which is a condition to be desired in a razor sharpener. With the parts made as shown in the drawings, the wheels are rotated substantially five and one-third revolutions during each stroke.

As the razor blade 75 advances over the wheel 103 or 104, as the case may be, it is resiliently urged against it by the escapement pawl 85. During the retrograde movement, the other side of the blade is resiliently urged against whichever wheel is in operative position by the escapement pawl 84. When the parts approach the right-hand position of Figure 1, the cam 90 rotates the blade and holder. The amount of rotation which the cam imparts to the blade and holder is exactly equal to the arcuate displacement of this truncated cylindrical cam. It will be seen that there is some additional distance for the blade 20 and holder to travel but this is taken care of by the springs 54 and also by inertia as the blade is practically spun around. However, the blade cannot spin beyond the desired position on account of the escapement action of the pawls 25 which will not allow continued rotation of the blade holder without relative reciprocal motion of the actuator 60 and carriage 46. Thus the pawls act as true escapement devices and also act as resilient pressing devices. Pressure may 30 be adjusted by turning the knob 81.

The holder of Figure 11 may readily be removed as follows: Keeping the clamping member 68 in the plane of the holding member 52, move the clamping member 68 until it is at right angles 40 to the holding member. This moves the arcuate portion of hook member 66 shown in Figure 11, which is in contact with the flange of the journal member, away from the journal member, thus permitting the entire assembly of holder 45 and clamping member to be moved away from and out of the supporting cross piece 57. When this has been done, the holder and clamping member can be readily lifted out. Referring now to Figures 16, 17, 18 and 19, I have therein shown a substitute holder and clamping member for a 50 Gem type of razor. This substitute holder and clamping member may be readily substituted for the Gillette type already described without any other change in the apparatus. It differs from the holder and clamping member already 55 described merely in the interlocking means that interlocks with the razor blade. As shown in these figures, the holding member 52a has arms 86a which cooperate with the escapement pawls 84 and 85 exactly as described, and it also has a tab 70a for interlocking with its clamping member 68a. Instead of the locking tabs 72, the holder 52a has a long slot 140 in which the back 60 of the Gem type of blade may fit, and in this slot is an offset supporting portion 141. The clamping member 68a has a corresponding offset portion 142 and the back of the Gem type of blade is held between these portions while the blade rests between the body portion of the 65 holder 52a and clamping member 68a. The clamping member 68a is connected to the holder 52a by means of a hook 66a which is articulated on a rivet 61a. The device is adapted to hone and strop both sides of the Gem razor, as will 70 be readily apparent without further description,

and a holder for any other variety of razor blade may be substituted for those shown.

Referring now to Figures 14 and 15, I may provide the structure therein shown, in which a single annulus has an abrasive ring which is a honing device on one side, and a fiber ring which is a stropping device on the other side, and this annulus may readily be picked off and turned over. Thus in this embodiment of the invention a pick-off type of wheel is used and a great 10 number of substitute wheels may be provided for obtaining different finishes, depending upon many factors such as the type of steel of the particular razor blade. As shown in these figures, I provide a gear 35a which meshes with the 15 driving gear 32 and this gear is integral with an upwardly extending sleeve 110a which is threaded at the top to receive a nut 127a. Interlocking with the gear 35a is a three-armed spider 101a which has three upward projections 115a formed by upsetting operations, leaving slots 116a extending to the outer ends of the arms of the spider and thus forming forked ends thereof which support an assembly comprising annuli 103a and 104a, and an interposed metal ring 150 20 having inwardly extending tabs 151 with slots therein, to which ring 150 are joined the two annuli 103a and 104a by a cementing operation or in any other suitable manner. The annulus 103a is the stropping annulus and may be made 25 of fiber, while the annulus 104a is the abrasive annulus for honing. In plan view, the ring 150 is exactly the same size as each of the annuli 103a and 104a. The upwardly extending projections 115a fit in the slots in the tabs 151. 30

I further provide a locking device consisting of a three-armed spring steel spider 155 located under the nut 127a and resting against a washer 156. The arms of this spider 155 rest on the tabs 151, but by loosening the nut 127a, a slight angular motion may be effected to move the arms off the tabs so that the annulus may be picked off and either turned over or a different one substituted therefor.

Referring now to Figures 23 to 31 inclusive, I have therein illustrated two additional embodiments of the escapement pawls and actuating mechanism for resiliently holding the blades in inclined positions, whereby the edges thereof may be stropped and sharpened, and for stopping the blade holder after the half revolution, more or less, given to it by the cam actuator 90. In the embodiment previously described, as will be remembered, the escapement pawls 84 and 85 are carried by the cover guard and actuator 60 which has a lost motion connection with the carriage 46. According to that embodiment, which of the escapement pawls 84 or 85 is pressing against the interposed arm 86 of the blade holder depends upon the position of the cover guard and actuator 60 with respect to the carriage 46. In the further embodiments of this mechanism shown in Figures 23 to 31 inclusive, there need be no lost motion connection between the cover guard and carriage, and the escapement pawls and associated mechanism are carried by the carriage itself, and the position of the pawls is determined by the direction in which the carriage is moving or has last moved in the box 30.

Describing first the embodiment of Figures 23 to 27 inclusive, and referring first to Figure 24, attached to one of the upwardly extending sides 48 of the carriage 46 and extending inwardly therefrom is an L shaped sheet metal supporting member 168 the shape of which is 70 75

sufficiently shown by comparing Figures 24, 25 and 26. This member 160 has a vertical part riveted to the side 48 and a horizontal part which supports a slide 170. The slide 170 may be made of sheet metal and has a pair of oppositely disposed bent-over tabs 171 and spaced therefrom another pair of oppositely disposed bent-over tabs 172, all of which tabs extend under the horizontal part of the member 160, as shown, 5 in order slidably to mount the slide 170 on the member 160. The slide 170 further has, as shown in Figures 23, 24 and 26, a pair of up-standing tabs 173, and a depending arm 174. The member 160 has an inwardly extending arm 175, and between the arms 174 and 175 extends a spring 176. The spring 176 draws the slide 170 to the right in Figure 24.

Referring now to Figures 24 and 25, riveted to the slide 170 and extending from the top 20 thereof is a stud 177. Pivotally mounted on the stud 177 is a block 180 made of any suitable material, which block has located in slots on its lower and upper sides respectively escapement pawls 184 and 185. The escapement pawls 184 25 and 185 are similar to the escapement pawls 84 and 85 and coat with an interposed arm 86 of a blade holder to tilt it one way or the other. However, the escapement pawls 184 and 185 have offset portions 186 and 187 which, as best 30 shown in Figure 27, engage a conical stud 188 which is in threaded engagement with the block 180, extending horizontally into the block as shown in Figure 27. By turning the stud 188, the pawls 184 and 185 may be forced apart more or less from the position shown in Figure 24. A nut 189 may be used to lock the stud 188 in adjusted position. The escapement pawls 184 and 35 185, like the pawls 84 and 85, are formed of spring steel and constitute resilient actuators 40 for the arm 86 to tip the blade holder.

The stud 177 extends through the pawls 184 and 185, as shown in Figure 24, and the pawls 184 and 185 and the block 180 are held on the stud 177 by nuts 190. A spacing washer 191 is desirably provided to hold pawl 184 against the block 180. Notwithstanding parts are secured together as described, they are angularly movable on the stud 177. Considering Figure 4, the right-hand side of the block 180 contacts the upper edge of the inside of the box 30. As shown in Figure 23, the contacting edge of the block 180 is arcuately shaped, and it will be remembered that the spring 176 urges the block 180 towards the side of the box 30. Consequently, relative 50 movement between the carriage 46 and the box 30 causes arcuate movement of the block 180 and escapement pawls 184 and 185 on the stud 177 until the block is stopped by one of the upstanding lugs 173. Owing to the fact that the pivot stud 177 is close to the side of the box and relatively remote from the actuating ends of the escapement pawls 184 and 185, very slight movement of the carriage in the box causes a given escapement pawl 184 or 185 to move away from 55 the interposed arm 86 and the other thereof to engage said arm. In other words, the razor blade is flopped over to present its opposite edge for actuation by one of the wheels by a reversal in movement of the carriage 46 for a very slight 60 distance.

The embodiment of Figures 23 to 27 inclusive otherwise operates according to the embodiment previously described, that is with respect to actuation by the cam actuator 90. Certain parts, 70 such as the cover guard actuator 60a, are of

slightly different shape in this embodiment of the invention to accommodate the mechanism described, and one of the ways for the cover guard comprising one of the sheet metal members 76 and associated parts is located in a slightly different position in this embodiment of the invention, as shown in the upper part of Figure 23 and also Figure 25. According to this embodiment of the invention, the cover guard 60a may or may not be connected to the carriage 46 by a pin and 10 slot connection, and an ordinary pivotal mounting for the cover guard will suffice.

Considering the further embodiment of Figures 28 to 31 inclusive, I provide an L shaped supporting member 160a on each side of the carriage 46 15 riveted to the upwardly extending sides 48 and supporting slides 170a having tabs 171a and 172a and each slide 170a having an upstanding tab 173a and a depending arm 174a connected by a spring 176a with an inwardly extending arm 20 175a of the supporting member 160a. These parts mentioned have the same function as already described in connection with the embodiment of Figures 23 to 27 inclusive. Mounted upon the slides 170a are blocks 180a by means of rivet 25 studs 177a. Mounted on each block 180a is one of a pair of escapement pawls 184a and 185a, as clearly shown in Figures 28 and 30. The operation of this escapement pawl mechanism is the same as in the case of the embodiment previous 30 described excepting that pawls 184a and 185a are located on opposite sides of the blade holder and each one is mounted on a pivotally mounted block mounted on a spring-pressed slide and, in this particular embodiment, no adjustment device such as the conical stud 188 is shown, but the escapement pawls 184a and 185a may be bent if it becomes desirable to adjust them. In the operation of a device according to the modification of Figures 28 to 31 inclusive, each of the 40 blocks 180a is moved whenever the direction of motion of the carriage 46 in the box 30 is changed, thus moving one of the two pawls 184a and 185a out of engagement with one of the arms 86 and moving the other of said pawls into engagement with the other of said arms. Accordingly, in this embodiment of the invention, the razor blade is inclined first one way during a forward stroke and then the other way during a retrograde stroke, and the cam actuator 90 operates in the manner previously described to turn the blade holder a half revolution more or less so that the other side of the cutting edges of the blade may be operated upon. In all the embodiments of the invention, the escapement pawls operate not only to incline the blade holders first one way and then the other but also to stop the revolution of the blade holder after it is actuated by the cam actuator 90. In other words, 45 they act effectively to prevent spinning of the 50 blade holder due to inertia thereof.

It will thus be seen that there has been provided by this invention an apparatus in which the various objects hereinabove pointed out together with many thoroughly practical advantages are 65 successfully achieved. As many possible embodiments may be made of the above invention and as many changes might be made in the embodiments above set forth, it is to be understood that all matter hereinbefore set forth, or shown in the 70 accompanying drawings, is to be interpreted as illustrative and not in a limiting sense.

I claim:

1. In a razor sharpener, an abrasive element, a carriage, a blade holder pivotally mounted on the 75

carriage arranged to move a razor in contact with said abrasive element, means to tip the blade holder to cause a razor to contact said abrasive element at an angle when the carriage is moved, a cover guard for the blade holder pivotally mounted on the carriage, and means on the cover guard interlocking with the blade holder when the cover guard is in an open position to prevent angular movement of the blade holder.

5. 2. In a razor sharpener, an abrasive element, a carriage, a blade holder mounted on the carriage whereby to move a blade past the abrasive element, and means to tilt the blade holder and give it a half turn whereby to move first one and then the other edge of a given side of the razor past the abrasive element and also to turn it over to present the other side of the blade to the abrasive element, said means comprising a pair of arms connected to the blade holder, a pair of resilient pawls adapted to contact the arms, a lost motion connection between the pawls and the arms, and a stationary cam having a cam surface formed in a hollow cylindrical element to turn the blade holder approximately one half 5 a revolution by contact with one of the pair of arms.

3. In a razor sharpener, a carriage, a blade holder mounted on the carriage, a first sharpening wheel having a plane annular radial sharpening surface, a second sharpening wheel having a plane annular radial sharpening surface mounted inside of, coaxial, and concentric with said first sharpening wheel, and means to elevate and lower one of said wheels whereby to place one of 30 the radial surfaces above the other selectively in order to present either of said surfaces to a blade held by the blade holder, the carriage being movable in a path perpendicular to the axis of both wheels to move the blade across one or 35 the other of said wheels depending on which thereof is elevated.

4. In a razor sharpener, a rotatable sharpening wheel, a carriage mounted for rectilinear movement, a blade holder pivotally mounted on 40 the carriage, a pair of projections one on each side of the blade holder, a pair of pawls to actuate a projection to incline the blade holder first in one direction and then in the other, and an arcuate wedge cam engageable with one of 45 the projections to turn the blade holder over.

5. In a razor sharpener, a rotatable sharpening wheel, a pinion gear connected to said sharpening wheel, a carriage, a rack attached to

the carriage, connections between the pinion and the rack whereby the wheel may be rotated when the carriage is moved, a blade holder holding a blade in inclined positions with a central median position of the blade in which it is parallel to the sharpening surfaces of the wheel, a pair of escapement pawls, means to move the pawls a limited distance in opposite directions, a lug connected to the blade holder in position to be actuated by first one and then the other of said 10 pawls to incline the blade in one direction for a forward stroke and the other direction for a rearward stroke of the carriage, and a stationary cam in a position to engage the same lug, said cam having a surface of revolution the axis of 15 which is parallel to movement of the carriage and said cam rotating said blade holder by action on said lug nearly one half a turn, the escapement pawls being so positioned that they do not interfere with such half revolution of the blade 20 holder.

6. In a razor sharpener, an abrasive element, a carriage, a blade holder mounted on the carriage, an actuator mounted in the carriage having a lost motion connection therewith, a pair 25 of arms extending laterally from the blade holder, a pair of escapement pawls connected to the actuator in position to engage the arms whereby the blade is tilted in one direction to contact the abrasive element when the actuator is moved 30 in a given direction and the blade is tilted in the opposite direction to contact the abrasive element when the actuator is moved in an opposite direction to the given direction, and stationary cam means to engage one of the arms to give the 35 blade holder a one half revolution at one end of the movement of the carriage.

7. In a razor sharpener for a double edged razor blade, an abrasive element, a carriage, a blade holder pivotally mounted on the carriage, 40 and means to revolve said blade holder on said carriage one half revolution for each complete reciprocation of said carriage, said means comprising cooperating spring and cam means resiliently to hold the blade holder in a given angular position, and a wedge cam shaped from a semi-cylindrical piece of metal mounted in the path of movement of the carriage and positioned to engage a lug at each reciprocation of the carriage, the cylindrical axis of the wedge cam 45 being substantially the same as the axis of pivotal mounting of the blade holder.

ANDREW F. BELL.
